UNITED STATES PATENT OFFICE

146,921

DESIGN FOR A KNIFE SHARPENER

Reuben B. Lambert, Erie, Pa., assignor to Super-edge Corporation, Erie, Pa., a corporation of Pennsylvania

Application December 3, 1945, Serial No. 124,297

Term of patent 14 years

(Cl. D37—1)

To all whom it may concern:

Be it known that I, Reuben B. Lambert, a citizen of the United States, residing at Erie, in the county of Erie and State of Pennsylvania, have invented a new, original, and ornamental Design for Knife Sharpeners, of which the following is a specification, reference being had to the accompanying drawing, forming a part thereof.

Figure 1 is a perspective, Fig. 2 is a side view, and Fig. 3 is a fragmentary top plan view of a knife sharpener showing my new design.

The appearance from the other side is substantially the same.

I claim:

The ornamental design for a knife sharpener, substantially as shown and described.

REUBEN B. LAMBERT.
